E. W. HOMER

HAIR WAVING IRON

Filed May 24, 1924

FIG. 1

FIG. 2

FIG. 3

Earl W. Homer
Inventor

By *Herbert E. Smith*

(Attorney)

UNITED STATES PATENT OFFICE.

EARLE W. HOMER, OF SPOKANE, WASHINGTON.

HAIR-WAVING IRON.

Application filed May 24, 1924. Serial No. 715,585.

To all whom it may concern:

Be it known that I, EARLE W. HOMER, a citizen of the United States, residing at Spokane, in the county of Spokane and State 5 of Washington, have invented certain new and useful Improvements in Hair-Waving Irons, of which the following is a specification.

My present invention relates to improvements in hair waving irons of the hand operated type and adapted especially for imparting to the hair a Marcel or similar wave. In most toilet articles of this character now on the market and utilizing a 15 pair of pivoted jaws of the scissors type, the relation of the jaws of the implement is such as to prevent proper and efficient operation of the device except when only a thin strand of hair is being pressed between the jaws. 20 And the devices now in use are incapable of properly performing their functions if the strand of hair to be waved is comparatively thick or brought into close proximity to the pivot of the jaws.

The primary object of my invention is the provision of means whereby the jaws may be spaced apart and will automatically adjust themselves to various thicknesses of strands of hair, and whereby the jaws are made to 25 be operative throughout their length. To accomplish this purpose, and overcome these objectionable features in existing devices, I provide a movable pivot member or rivet and construct the jaws at their pivot points 30 in such manner that they are movable with relation to the pivot and may be adjusted automatically for accommodating various thicknesses of strands of hair. The device as thus constructed and arranged is simple 35 in construction and operation and comparatively inexpensive in cost of production. The invention consists in certain novel combinations and arrangements of parts involving a pair of pivoted jaws of the scissors 40 type each having a slotted head, a pivot member in the slots, and means carried by a handle of the device for co-action with a jaw connected with the opposite handle, for retaining the jaws in adjusted position, together with other features of construction, 45 as will hereinafter be more fully pointed out and claimed.

In the accompanying drawings I have 50 illustrated one complete example of the physical embodiment of my invention wherein the parts are combined and arranged in

accordance with the best mode I have thus far devised for the practical application of the principles of my invention.

Figure 1 is a perspective view of a curling 60 iron or waving iron constructed according to and embodying the principles of my invention.

Figure 2 is an enlarged detail view partly 65 in section showing the pivotal connection of the jaws, the adjusting spring and the tension adjusting means for the spring.

Figure 3 is an enlarged detail view partly 70 in section showing by dotted lines the adjustment of the relatively movable jaws.

In carrying out my invention I utilize the well known type of pivoted jaws 1 and 2, preferably V-shape in cross section, the inner jaw or iron 1 of which may be solid and the outer jaw open or hollow to fit thereover, 75 and one or both being adapted for heating and use in usual manner. The respective jaws have crossed handles or integral shanks 3 and 4 and the shank 3 has an open head 5 to receive the complementary head 6 of the 80 shank 4. Both heads are fashioned with complementary slots, a single slot 7 being provided in the head 5 and a pair of slots 8 alined therewith are provided in the open head 6. Through these registering slots 85 a pivot pin or rivet 9 is passed and provided with retaining heads 10 at both its ends to hold the heads in frictional engagement, but of course permit relative movement of the heads on the pivot. 90

Through this slot and pin connection the two heads are loosely supported and relatively movable on their pivot member, but a flat leaf spring 11 is provided to afford resilient and adjustable means for retaining 95 them in operative position. This spring is carried by the shank 4 to which it is secured at one end by means of a screw 12, and the free end 13 of the spring has a frictional bearing on the head 5 of the shank 3 and 100 jaw 1, thus holding the jaw 1 and its head 5 in proper relation to the complementary outer jaw 2 and its head 6. It will be noted that the longitudinal axis of the slots is at 105 a slight angle to the perpendicular with relation to the longitudinal axis of the jaws, and that the jaws while in parallelism, may be spaced apart substantially the length of the slots. Regardless of the relative position of the jaws they are pivoted on the pin 110 or rivet 9 and may be moved with the pin as a center. Thus the jaws may be sepa-

rated, against the tension of the spring 13 to accommodate various thicknesses of strands of hair, and the arrangement of the inner head within the open head permits 5 relative movement of these parts, but prevents lateral movement or wabbling of the pivoted members. As indicated in Fig. 3 by dotted lines a thick strand of hair may be accommodated near the pivot point or 10 fulcrum to receive the application thereto of the lever action of the implement for compressing the strand in the formation of a wave. The jaws, when in parallelism, are also capable of operating on a strand of 15 hair that may extend from the free ends of the jaws to the pivoted heads, and the application of power will be uniform throughout the length of the jaws. In this manner a wave or crimp of uniform quality may be 20 imparted to the hair which will be of a length corresponding to the length of the implement from the pivot to the ends of the jaws.

The implement is provided with two 25 handles, of which handle 14 is fixed on the shank 3, and the handle 15 is rotatable on the threaded end 16 of the shank 4. The rotatable handle is designed to co-act with 30 its shank for regulating the tension of the spring 11 and is fashioned with a threaded sleeve portion 15' the free or open end of which may be rotated around the spring 11. As the screw motion is given to the rotary 35 handle it is projected toward the pivot and toward the free end of the anchored spring for the purpose of riding down the spring and holding it in close contact with the shank 4. This action reduces the length of 40 the resilient portion of the spring and tends to increase its rigidity and application of power to the head 5.

For retaining the adjustable handle in adjusted position and preventing accidental rotation of the handle I utilize a snap spring 45 or pawl 17 located in a groove and carried by the sleeve portion 15' of the handle 15. As the handle is turned this snap spring or pawl will engage with a selected one of several longitudinal slots 18 in the shank 4, and

prevent rotation of the sleeve and handle, 50 except when force is applied thereto for the purpose.

Having thus fully described my invention, what I claim as new and desire to secure by Letters Patent is—

1. In a device as described the combination with pivoted jaws each having a handle and a slotted head, of a pivot member in the slotted heads whereby the jaws may be spaced substantially apart, and means carried by one handle for co-action with the head of the other handle for retaining said jaws in adjusted position.

2. The combination with pivoted jaws each having a handle and a slotted pivot head whereby the jaws may be spaced substantially apart, of resilient means carried by one handle for co-action with the head of the other handle for retaining said jaws in adjusted position, and means for varying 70 the resiliency of the retaining means.

3. The combination with pivoted jaws each having a handle and a slotted pivot head whereby the jaws may be spaced substantially apart, of a spring carried by one 75 handle and having a bearing against the head of the other handle for retaining said jaws in operative position.

4. The combination with pivoted jaws each having a shank and a slotted pivot head whereby the jaws may be spaced substantially apart, of a flat spring having an end fixed to one shank and bearing against the head of the other shank, and an adjustable handle on the first shank adapted to vary 80 the tension of the spring.

5. The combination with pivoted jaws each having a shank and a slotted pivot head whereby the jaws may be spaced substantially apart, of a flat spring having an end fixed to a shank and bearing against the head of the other shank, screw threads on the end of the first shank, and a threaded handle-sleeve on the first shank adapted to vary 85 the tension of the spring.

In testimony whereof I affix my signature.

EARLE W. HOMER.
